(57) **CLAIM**

The ornamental design for a shoe, as shown and described.

DESCRIPTION

FIG. 1 is a front perspective view of a shoe showing my new design;

FIG. 2 is a top view thereof; and

FIG. 3 is a rear perspective view thereof;

FIG. 4 is a side view thereof;

FIG. 5 is an opposite side view thereof;

FIG. 6 is an enlarged view of FIG. 1 with environmental portions removed for clarity;

FIG. 7 is an enlarged view of FIG. 2 with environmental portions removed for clarity;

FIG. 8 is an enlarged view of FIG. 3 with environmental portions removed for clarity; and,

FIG. 9 is an enlarged view of FIG. 4 with environmental portions removed for clarity.

The broken lines immediately adjacent to and surrounding the photographic area define the peripheral bounds of the claimed design and form no part thereof. The broken lines showing the remainder of the shoe are for environmental purposes only and form no part of the claimed design.
